UNITED STATES PATENT OFFICE.

ROY A. MUNSON, OF FREEPORT, ILLINOIS.

DRIVE UNIT FOR STOKERS.

Application filed April 19, 1924. Serial No. 707,635.

To all whom it may concern:

Be it known that I, ROY A. MUNSON, a citizen of the United States, residing at Freeport, in the county of Stephenson and State of Illinois, have invented certain new and useful Improvements in Drive Units for Stokers; and I do hereby declare the following to be a full, clear, and exact description of the invention, such as will 10 enable others skilled in the art to which it appertains to make and use the same.

My invention relates to a drive unit for locomotive stokers, and has for its object to provide a strong, simple, cheap and durable mechanism which will efficiently and reliably operate under the conditions of service to which locomotive stokers are subjected.

The well known type of stoker illustrated in the drawings, for the purpose of explaining the relation of my invention thereto, is equipped with three drive units, one being located at the head of each of the upwardly extending screw conveyors and one being employed for controlling the horizontal conveyor screw associated with the transfer hopper. These drive units provide means for rotating the several conveyor screws in either direction which the necessities of service may require. In the drive units at present used in such locomotive stokers the forward and reverse driving pawls are connected through the intervention of a coiled tension spring. The life of these tension springs is comparatively short in service, and as they frequently break corresponding engine failures often occur. By my invention the liability of the stoker drive units to fail and thus cause engine delays is substantially eliminated, and experience has proven that drive units constructed in accordance with the invention operate efficiently over very long periods without requiring attention.

The principal feature of the invention, generally stated, consists in constructing the drive unit with a ratchet wheel driving member and a revolvable driven member, the latter being driven by the ratchet wheel through the intervention of pawl mechanism carried by the driven member, the said pawl mechanism including one or more pairs of pivoted pawls serving as a means whereby the ratchet wheel may rotate the driven

member either forwardly or in reverse direction, the pawls of each pair being yieldingly connected through an interposed compression spring which operates to cause the pawls to swing towards each other, and means being provided whereby either pawl 55 of a pair may cooperatively engage the ratchet wheel while the other pawl is disengaged from said wheel.

A further feature of the invention consists in providing the drive unit with a 60 ratchet wheel driving member, a revolvable driven member, and pawl mechanism mounted on the driven member for cooperating with the ratchet wheel to enable the driven member to be rotated either forwardly or in reverse direction, the pawl mechanism including a plurality of pawls 65 yieldingly connected in one or more pairs, the means for connecting a pair of pawls comprising a coiled compression spring and 70 a plurality of overlapping pins which slide through the spring and constitute means for compressing the latter.

Further features of the invention residing in particular arrangements of parts and 75 advantageous structural details will herein-after appear and be particularly pointed out in the claims.

In the drawings chosen for the purpose of illustrating the invention,—

Figure 1 is a view, partly in side elevation and partly in section, of a locomotive stoker having a drive unit embodying the invention applied thereto.

Figure 2 is a detail elevation of the drive 90 unit, the cover of its casing being removed.

Figure 3 is a detail view on a more enlarged scale, showing the preferred form of means for yieldingly connecting the pawls of the drive unit.

Figure 4 is a detail elevation of the relatively movable pins forming a part of the device for yieldingly connecting the pawls.

Figure 5 is a perspective view of one of the members by which the spring controlling a pair of pawls is compressed.

As is well known, the type of locomotive stoker illustrated in the drawings is provided with two upright elevator casings, such as 1, within each of which is an elevator screw 2. The elevator screws 2 are in communication with a transfer hopper 3 which is fed with fuel by a horizontally

extending conveyor screw 4. These several screws are respectively revolved, either forwardly or in reverse direction as the case may require, by drive units 5 of substantially identical construction, two of which control the operation of the elevator screws 2 and the other of which governs the movement of the conveyor screw through the flexible drive shaft 6 and the usual gearing (not shown).

The drive unit comprises a revoluble ratchet wheel 7 which is caused to rotate first in one direction and then in the other. In the case of the drive unit for the conveyor screw 4 feeding the transfer hopper, the back and forth rotation of the ratchet wheel 7 is effected by a corresponding movement of the drive shaft 8 to one end of which the ratchet wheel is secured by means of keys 9, the opposite end of the shaft being provided with a pinion 10 which is rotated by the stoker engine (not shown) through the usual rack bar 11. The corresponding ratchet wheels of the drive units for the elevator screws 2 are similarly rotated by the elevator shafts 12 which pass axially through the elevator screws 2.

Encircling the ratchet wheel 7 is a casing 13 which is adapted to revolve freely upon the shaft 8. Pivotaly mounted within this casing, as by means of pivot pins 14, are a plurality of pawls 15 and 16, respectively, which are arranged in pairs and yieldingly connected. Each pair of pawls comprises a pawl 15 and a pawl 16, the pawl 15 being termed the forward conveyor pawl by reason of the fact that it serves to communicate forward movement to the conveyor screw with which it is associated, and the pawl 16 being known as the reverse conveyor pawl because it communicates reverse motion to its conveyor screw.

As shown in Fig. 2, only one of the pawls 15 and 16 of each pair is in engagement with the ratchet wheel 7 during the operation of the drive unit; that is to say, when the forward pawls cooperate with the ratchet wheel, the reverse pawls 16 are disengaged from said wheel, and vice versa. The shifting of the pawls 15 and 16 to the positions required for imparting forward or reverse movement to the conveyor screws may be controlled by the well known form of pawl shifter 17 provided with projecting arms or fingers 18 which extend through slots in the revoluble casing 13 so as to operate between the pawls of the respective pairs. When the lever 19 is manipulated the pawl shifter which it controls is caused to slide and also to revolve, thus enabling the fingers 18 of the shifter to selectively disengage the pawls from the ratchet wheel 7. Each of the fingers 18 is preferably provided with the usual angle slot 20 for receiving a plug or pin 21 carried by the cas-

ing 13, the necessary rotary movement of the pawl shifter being effected by these well known means.

The forward pawl 15 and the reverse pawl 16 of each pair are yieldingly controlled by a compression spring 22 which encircles a pair of relatively slidable pins or bars 23. These sliding pins are preferably of identical form and each one of them is pivotally connected to one of the pawls by a pin 24 which may advantageously pass through an eye 25 formed in an enlarged head 26 fashioned at one end of the pin. At its opposite end each pin is formed with a flange or shoulder 27 adapted to form a follower for cooperating with the adjacent end of the compression spring 22 encircling both pins, the heads 26 and the respectively adjacent flanges 27 being so related that the pivot pin openings 25 in the said heads 26 may be disposed centrally in alignment with the axis of the compression spring 22. As the result of this construction the separation of a pair of pawls 15 and 16 effects a compression of the intervening spring 22. The pawl mechanism is preferably protected by a suitable cover 28 rigidly connected to the revoluble pawl casing 13 by threaded pins or bolts 29. The connection of the drive unit with the flexible drive shaft 6 is effected through this casing cover 28.

The operation of the drive unit will be readily understood upon reference to Fig. 2. When the ratchet wheel 7 rotates in a counter-clockwise direction the forward pawls 15, which are pivotally mounted upon the casing 13 through the pivot pins 14, cause the said casing 13 to perform a forward rotation corresponding to the similar rotation of the ratchet wheel. As the reverse pawls 16 are also mounted upon and move with the casing 13, the relative position of the pawls of each pair remains unchanged during this operation and the spring 22 is unaffected. When, however, the ratchet wheel 7 is reversed and turns in a counter-clockwise direction, the springs 22 through which the pawls are connected are compressed sufficiently to permit the forward pawls 15 to ratchet over the teeth of the wheel 7. Upon the ratchet wheel subsequently rotating forwardly or in counter-clockwise direction, the forward pawls 15 again communicate a forward rotation to the casing 13. By a similar mode of operation the casing 13 is caused to rotate reversely when the reverse pawls 16 are in engagement with the ratchet wheel 7 and the forward pawls 15 are disengaged therefrom.

It will be observed that my invention not only makes the use of compression springs practically possible for the control of the pawls of stoker drive units, but also

that the construction is such that the springs have the same amount of expansion and compression whether the pawls are in forward or in reverse position, for as one pawl goes out of engagement with the ratchet wheel 7 the other moves into engagement, thus maintaining the same distance between the pawls. This is a matter of importance in that the spring is therefore able to operate under the best conditions conducive to long and efficient service, not being required to operate at the extreme limits of its power. It will also be observed that the construction enables both pawls of a pair to be actuated by a single compression spring which is in constant operation regardless of the positions of the pawls, and that the elimination of any rust or foreign matter which otherwise might accumulate and render the pawl mechanism inoperative is thus effected. This is advantageous since the stoker on a locomotive is usually operated in the forward position for long periods of time, and the reverse pawls of the driving mechanism are only called into service occasionally when it is necessary to remove obstructions or clogs. Another advantage of my invention is that the slideable pins or members 23, which are preferably cast of brass or steel and do not require any machine work, support the pawl controlling springs against distortion. The particular form of yielding control of the pawls embodied in my invention also has the added merit of being readily applicable to stokers of this type.

I claim:—

1. A drive unit for stokers involving a ratchet wheel, means for alternately rotating said ratchet wheel in opposite directions, revolubly mounted means adapted to rotate both forwardly and in reverse direction, at least one pair of pivoted pawls whereby said last named means may be caused to rotate either forwardly or in reverse direction, the pawls of said pair being yieldingly attached to each other through the intervention of compression spring means tending when compressed to pull the pawls toward each other, one of said pawls being adapted to cooperate with said ratchet wheel to drive said revolubly mounted means in one direction and the other of said pawls being adapted to cooperate with said ratchet wheel to drive the said revolubly mounted means in the reverse direction, and means for permitting either pawl of said pair to engage and cooperate with said ratchet wheel while the other pawl is disengaged from said ratchet wheel.
2. A drive unit for stokers involving a ratchet wheel driving member, a revoluble driven member encircling said driving member, pawl mechanism movably mounted on said driven member and adapted to cooperate with said ratchet wheel, said pawl mech-

anism including at least one pair of pivoted pawls whereby said driven member may be caused to rotate either forwardly or in reverse direction, compression spring means interposed between and yieldingly connecting the pawls of said pair between the pivotal points thereof and said ratchet wheel, said means serving to permit the free ends of the pawls to separate relatively to each other, and means for permitting either pawl of said pair to engage and cooperate with said ratchet wheel while the other pawl is disengaged from said ratchet wheel.

3. A drive unit for stokers involving a revoluble driving member, a revoluble driven member, one of said members having ratchet teeth and the other being provided with pawl mechanism movably mounted thereon and cooperating with said ratchet teeth to form a driving connection between said driving member and said driven member, said pawl mechanism including at least one pair of relatively movable pawls whereby said driven member may be caused to rotate either forwardly or in reverse direction, compression spring means extending between and yieldingly connecting the pawls of said pair, said spring means including relatively slideable members each pivoted to one of said pawls, and means for permitting either pawl of said pair to engage and cooperate with said ratchet teeth while the other pawl is disengaged from said teeth.

4. A drive unit for stokers involving a revoluble driving member, a revoluble driven member, one of said members having ratchet teeth and the other being provided with pawl mechanism cooperating with said teeth to form a driving connection between said driving member and said driven member, said pawl mechanism including at least one pair of pivoted pawls whereby said driven member may be caused to rotate either forwardly or in reverse direction, spring means interposed between and yieldingly connecting the pawls of said pair, said spring means involving a compression spring and a plurality of relatively movable members for compressing said spring, each of said spring compressing members being movably connected to one of said pawls, and means for permitting either pawl of said pair to engage and cooperate with said ratchet teeth while the other pawl is disengaged from said teeth.

5. A drive unit for stokers involving a ratchet wheel driving member, a revoluble driven member, pawl mechanism mounted on said driven member and cooperating with said ratchet wheel driving member to cause said driven member to rotate either forwardly or in reverse direction, said pawl mechanism including at least one pair of pivoted pawls, spring means interposed between and yieldingly connecting the pawls

of said pair, said spring means involving a coiled compression spring and a plurality of relatively movable pin members extending through said spring and constituting means for compressing said spring, each of said pin members being pivotally connected to one of said pawls, and means for enabling

either pawl of said pair to engage and co-operate with said ratchet wheel driving member while the other pawl is disengaged 10 from said ratchet wheel member.

In testimony whereof I affix my signature.

ROY A. MUNSON.
